(57) **CLAIM**

The ornamental design for a coin tube organizer, as shown and described.

DESCRIPTION

FIG. 1 is a top plan view of a coin tube organizer showing my new design;

FIG. 2 is a right side elevational view with the left side being a mirror image thereof;

FIG. 3 is a front elevational view with the rear being a mirror image thereof; and,

FIG. 4 is an environmental perspective.

The broken line showing of the coin tube in FIG. 4 is for illustrative purposes only and forms no part of the claimed design.
